DESIGN FOR A HOLDER FOR A SALT
BLOCK

Malcolm F. MacLean, Swampscott, Mass., assignor to International Salt Co., Inc., Scranton,
Pa., a corporation of New York

Application December 13, 1938, Serial No. 81,758

Term of patent 14 years

To all whom it may concern:

Be it known that I, Malcolm F. MacLean, a citizen of the United States and a resident of Swampscott, in the county of Essex and Commonwealth of Massachusetts, have invented a new, original, and ornamental Design for a Holder for a Salt Block, of which the following is a specification, reference being had to the accompanying drawing, forming a part thereof, in which the figure is a view in perspective of a holder for a salt block, showing my new design.

I claim:

The ornamental design for a holder for a salt block, substantially as shown.
